UNITED STATES PATENT OFFICE.

WILLIAM A. LORENZ, OF HARTFORD, CONNECTICUT.

ABRASIVE PAPER.

Application filed January 4, 1921. Serial No. 434,941.

This invention relates to emery and other abrasive papers, and its object is to produce at a low cost an inexpensive flexible fabric of this character.

5 To prepare the paper for receiving the abrasive material, it is rendered flexible and limp by preferably corrugating it longitudinally and then crinkling it transversely, and then tentering the paper or pulling it or 10 ironing it substantially smooth. The paper is then highly flexible or limp; and the abrasive material is applied thereto in a well-known manner. While I show the form of corrugated and crinkled paper that is 15 disclosed in my application No. 333,750, filed October 27, 1919, and while I also show this paper smoothed out as disclosed in my application No. 407,399, filed September 1, 1920, still it will be understood that other 20 forms and methods of corrugating and crinkling may be employed, and the gathered paper may be otherwise smoothed out.

Other features and advantages will hereinafter appear.

25 In the accompanying drawings,

Figure 1 shows a section of paper which has been first corrugated in one direction and then crinkled transversely.

Figure 2 shows a sheet of paper that 30 has been smoothed out after being gathered.

Figure 3 shows the Figure 2 product to the surface of which abrasive material has been applied to form a flexible emery or abrasive paper.

35 Figure 4 is a cross-section on line 4-4 of Figure 3.

Figure 5 is a diagram of a buffing wheel upon which the flexible emery paper has been applied.

40 The paper 10 has preferably longitudinal corrugations 11 and transverse crinkles 12, whereby it is rendered stretchable in all directions; but the paper may be otherwise gathered transversely and longitudinally.

45 This product, in which the fibres are limbered, is then stretched or smoothed out, and has the feeling of soft cloth. This effect is produced by the limbering and breaking up of the fibres by the gathering operations and the subsequent smoothing out 50 operation.

To the surface of this material 13 there is applied an abrasive material 14, thus producing a highly flexible abrasive fabric at low cost.

55 At Figure 5 is shown a buffing wheel or drum 15 having the novel fabric wrapped thereon. In the periphery of the wheel may be formed a V-shaped notch 15^a, in which the ends 16 of the fabric are held by means 60 of a wedge-like key 17.

The paper 13, since it is flexible and resembles cloth in its nature, remains flexible after the abrasive has been applied to one face thereof. This flexibility enables the 65 abrasive paper to be bent easily and closely where required, as, for example, around the buffing wheel. Paper of this nature is not so brittle as a stiff paper which has the abrasive material applied to its smooth 70 surface, nor does it so readily crack; and it lends itself readily to be applied to various devices for sand-papering and other purposes.

75 Variations may be resorted to within the scope of the invention, and portions of the improvements may be used without others.

Having thus described my invention, I claim:

1. The process of gathering paper in 80 transverse directions to limber the fibres thereof, then smoothing out the paper, whereby it is rendered flexible, and then applying an abrasive material to the surface thereof to produce a flexible or limp abrasive sheet.

2. An abrasive paper having its fibres disturbed, loosened and limbered to increase 85 its flexibility, the paper being relatively flat, and a substantially unbroken coating of 90 abrasive material applied to at least one surface of said paper.

3. An abrasive paper comprising paper having its surface fibres on opposite sides broken or distorted while the middle fibres 95 are less disturbed, said paper being relatively flat, and an abrasive material applied to one at least of the surfaces of said paper.

WILLIAM A. LORENZ.
